UNITED STATES PATENT OFFICE.

JOHN B. STEVENS, OF MACON, GEORGIA.

BRAKE ATTACHMENT FOR RAILWAY-CARS.

1,108,526.

Specification of Letters Patent. Patented Aug. 25, 1914.

Application filed January 26, 1914. Serial No. 814,566.

To all whom it may concern:

Be it known that I, JOHN BERRY STEVENS, a citizen of the United States, residing at Macon, in the county of Bibb and State of Georgia, have invented a new and useful Brake Attachment for Railway-Cars, of which the following is a specification.

The present invention appertains to a brake attachment for railway cars, and aims 10 to provide a novel and improved appliance of the nature indicated, which will be automatically operable to open the air line, or train pipe, should the wheels of the truck to which the attachment is applied, become 15 derailed, or should the arch bars of the truck break, or other accident of that nature occur.

Another object of the present invention is to provide a contrivance of the character mentioned, which may be readily applied to 20 a car truck, and air line or train pipe, and which embodies means coöperable with the rails for opening the air line or train pipe, should the wheels become derailed, whereby the usual automatic air brakes will be set or 25 brought into operation.

It is also within the spirit of the present invention, to provide a unique assemblage of parts to the ends above noted, and whereby the present structure will be comparatively 30 simple and inexpensive, may be readily applied to various car trucks, and will be simple, practical and efficient in its use.

With the foregoing general objects outlined, and with other objects in view, which 35 will be apparent as the nature of the invention is better understood, the present invention resides in the combination and arrangement of parts and in the details of construction hereinafter described and claimed, it 40 being understood that changes in the precise embodiment of the invention herein disclosed, can be made within the scope of what is claimed, without departing from the spirit of the invention.

45 The invention has been illustrated in its preferred embodiment in the accompanying drawing, wherein:—

Figure 1 is a plan view of a car truck illustrating the attachment applied thereto, 50 and as connected to the air line or train pipe. Fig. 2 is a transverse section of the truck, taken on the line 2—2 of Fig. 1. Fig. 3 is a sectional detail taken on the line 3—3 of Fig. 1. Fig. 4 is a perspective view of one

of the slides forming a part of the present 55 attachment.

In the drawing, the numeral 1 designates an ordinary or arbitrary car truck, embodying the sand bolster 2 between the two pairs 60 of wheels.

The numeral 3 designates the air line or train pipe, which is carried by the bottom of the car body (not shown).

The foregoing parts are well understood in the art, and need not be described at 65 length.

In carrying out the present invention, a transversely disposed pipe 4 is mounted at one side of the truck bolsters, and is carried by upstanding brackets 5 secured to one side 70 of the sand bolster 2 and having eyes or bearings at their upper ends receiving the end portions of the said pipe 4. Attached to the pipe 4, intermediate its ends, is a hose section 6, and a similar hose section 7 is connected to a T-coupling disposed in the air line or train pipe 3, the hose sections 6 and 7 carrying the interlockable coupling members 8 at their free ends, whereby the pipe 4 may be readily coupled to the train pipe 3, the 80 hose sections 6 and 7 permitting of the movements of the truck and car body relative to each other without interfering with the connection between the pipe 4 and train pipe 3. A valve 9 is preferably interposed between the hose section 7 and the train pipe 3, whereby the valve 9 may be closed, when desired, to render the present attachment 85 inoperative, as when the hose sections 6 and 7 are uncoupled to enable the truck and car 90 body to be separated, or for other purposes. Ordinarily, however, when the present device is in operation, the valve 9 is open. To the ends or terminals of the pipe 4, are attached cocks 10, the valve stems of which 95 have the angular handles or levers 11, which normally project horizontally away from each other, when the valves are closed. The valves of the cocks 10 are arranged to be opened when the levers 11 are swung upwardly by the devices presently described.

An actuating device is carried by the truck, adjoining each rail, each of the said devices embodying a U-shaped slide or hanger 12 having its arms slidably engaging 105 through guides 13 and 14 secured to the opposite sides of the sand bolster 2. The guides 13 and 14 are of channel shape, the

arms of the slide 12 being provided with slots 15 through which adjustable stops or supporting pins 16 carried by the guides engage to support the slide 12 at any vertical position. The arm of the slide 12 which 5 slidably engages the guide 13, is provided at its extremity or free end with a fork 17, offset away from the truck bolsters, and having its branches each provided with a series 10 of apertures 18. The butt end of a finger 19 is adapted to be secured within the fork 17 by means of a bolt or other securing member 20 passed through the alining apertures 18 of the branches of the fork 17. 15 The slides 12 are disposed directly beyond the cocks 10, and the levers 11 are adapted to normally rest upon the fingers 19 carried by the slides, the fingers 19 projecting inwardly toward the valve stems, whereby 20 when the slides 12 are raised or elevated, the valves or spigots of the cocks 10 will be readily and effectively opened to open the air line or train pipe. It is evident that the fingers 19 may be adjusted within the 25 forks 17 to properly accommodate the levers 11, according to the vertical adjustments of the slides 12.

Each of the slides 12 is provided with means associated with the respective rail 30 of the track, for facilitating the elevation of the slide should the truck wheels become derailed. To this end, a lever 21 is pivoted or fulcrumed intermediate its ends to the yoke portion or cross piece of the slide 12, by means of a clip or other bearing 22. Coiled wire compression springs 23 are disposed between the ends or arms of the lever 21 and the bottom of the sand bolster 2, the opposed springs being normally balanced, to 35 hold the lever 21 in a horizontal position. The slides 12 are disposed directly inside of the rails, in order that the outer arms of the levers 21 overhang the rails while the inner arms of the levers project toward each 40 other, and have an open and unencumbered space therebetween below the sand bolster, whereby such parts of the brake apparatus, as need be, may be extended centrally below the sand bolster without interfering with 45 the present attachment.

In practice, the present attachment may be readily applied to the trucks of various railway cars without entailing any appreciable alterations or expense. The hose sections 50 6 and 7 which may be readily coupled and uncoupled, permit of a quick and convenient connection and disconnection of the pipe 4 of the attachment to and from the air line or train pipe 3, as well as permitting the truck and car body to have the 55 usual movements relative to each other, such as when rounding curves. The slides or hangers 12 may be readily adjusted within the guides 14, by properly setting the stops 60 or supporting pins 16, whereby the levers 21

may be properly disposed above the rails for coöperation therewith. The fingers 19 may also be readily adjusted to properly coöperate with the levers 11 of the cocks or valves 10, as above intimated.

Particular attention is directed to the fact that the parts of the present attachment, which are associated with the truck, are all carried by the sand bolster, which is carried at a practically uniform distance above the 75 rails at all times, thus enabling the levers 21 to be properly carried above the rails without any appreciable variation.

Under normal conditions, should the ends or arms of the levers 21 encounter non- 80 injurious objects along the rails, the levers 21 will swing slightly upon the yoke portions of the slides 12 as fulcrums, whereby the slides would not be appreciably raised. In this manner, the arms of the levers 21 are adapted to yield slightly without effecting the positions of the slides 12.

Should one or the other, or both of the rails of the track be broken, so as to let the wheels of the truck drop, the outer arm of the respective lever, or the outer arms of both of the levers, whichever is the case, would be forcibly seated upon the rail or rails, so as to cause the slide or slides to be raised, thereby opening one or both of 95 the cocks 10 and permitting the air to escape from the air line or train pipe 3, so as to set the usual automatic air brakes for stopping the train. Similarly, should the truck become derailed, the inner arm of that 100 lever 21 at that side toward which the wheels are derailed, would seat upon the respective rail, so as to raise the corresponding slide 12 for opening the air line or train pipe to set the automatic air brakes. The 105 air line or train pipe will also be opened should both arms of one or both of the levers 21 be raised relative to the sand bolster 2, as will be manifest.

From the foregoing, taken in connection 110 with the drawing, the advantages of the present attachment will be obvious to those skilled in the art, the present attachment being intended for automatically opening the air line and setting the automatic air 115 brakes, should the truck wheels become derailed or dangerously encumbered, or should the arch bars of the truck break or a similar accident occur. The present attachment does not appreciably encumber the 120 truck, and is so disposed, as not to be readily interfered with.

Having thus described my invention, what I claim as new is:—

1. In a brake attachment, a brake applying device, a vertically movable slide operatively connected thereto, and a spring pressed lever fulcrumed to the slide for co-operation with the rail.

2. In a brake attachment, a brake apply-

130

ing device, a vertically movable slide operatively connected thereto, a lever fulcrumed intermediate its ends to the slide, and balanced springs coöperating with the arms of the lever.

3. In a brake attachment, a valve adapted for connection to a train pipe, a vertically movable slide coöperable with the said valve to open the same, and a spring pressed lever fulcrumed to the slide for coöperation with a rail.

4. In a brake attachment, a valve adapted for connection to a train pipe, a vertically movable slide coöperating with the valve to open the same, a lever fulcrumed intermediate its ends to the slide, and balanced springs coöperating with the arms of the lever.

5. The combination with a car truck, of a brake applying device carried thereby, a guide carried by the truck, a slide movable through the guide and operatively connected to the said device, and a spring pressed lever carried by the lower portion of the slide for coöperation with a rail.

25 6. The combination with a car truck, of a brake applying device carried thereby, a guide carried by the truck, a slide movable through the said guide and operatively connected to the said device, a lever fulcrumed intermediate its ends to the lower portion of the slide, and balanced springs disposed between the arms of the said lever and the truck.

7. The combination with a car truck, of a valve carried by the truck and arranged for connection to the train pipe, a guide carried by the truck, a slide movable through said guide and having means coöperating with the said valve to open the same, and a spring 35 pressed lever carried by the lower portion of the slide for coöperation with a rail.

8. The combination with a car truck, of a valve carried by the truck and arranged for connection to the train pipe, a guide carried by the truck, a slide movable through said guide and having means coöperating with the said valve to open the same, a lever fulcrumed intermediate its ends to the lower portion of the said slide, and balanced 45 springs disposed between the arms of the said lever and the truck.

9. The combination with a car truck, of a valve carried by the truck and arranged for connection to the train pipe, a guide attached to the truck, a slide movable through the said guide, adjustable means carried by

the said slide and coöperable with the said valve to open the same, adjustable means for supporting the slide from the guide, and means carried by the lower portion of the slide for coöperating with a rail.

10. The combination with a car truck including a bolster, of guides secured to the sides of the bolster, a U-shaped slide having its arms passing through the said guides, adjustable means for supporting the slide from the guides, a valve carried by the said bolster and arranged for connection to the train pipe, adjustable means carried by the other arm of the slide and coöperable with the valve to open the same, and means carried by the yoke portion of the slide for coöperation with a rail.

11. The combination with a car truck including a bolster, of a U-shaped slide having its arms slidably carried by the sides of the bolster, a valve carried by the said bolster and arranged for attachment to the train pipe, coöperating means carried by the said slide and valve for opening the valve, a lever fulcrumed intermediate its ends to the yoke portion of the said slide below the bolster, and balanced springs disposed between the arms of the said lever and the bolster.

12. The combination with a car truck, including a bolster, of guides secured to the sides of the bolster, a U-shaped slide having its arms passing through the said guides, adjustable means for supporting the slide from the guides, a brake applying device carried by the bolster, adjustable means operatively connecting one arm of the slide and the said device, and means carried by the yoke portion of the slide for coöperation with a rail.

13. The combination with a car truck, including a bolster, of a U-shaped slide having its arms slidably carried by the sides of the bolster, a brake applying device carried by the bolster, means operatively connecting the slide and said device, a lever fulcrumed intermediate its ends to the yoke portion of the slide below the bolster, and balanced springs disposed between the arms of the said lever and the bolster.

In testimony that I claim the foregoing as my own, I have hereto affixed my signature in the presence of two witnesses.

JOHN B. STEVENS.
